UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

Application filed March 23, 1922. Serial No. 545,924.

To all whom it may concern:

Be it known that I, FRANKLIN R. WHITE, a citizen of the United States, and a resident of Waterbury, in the county of New Haven and State of Connecticut, have made and invented certain new and useful Improvements in Buttons, of which the following is a specification.

My invention relates to buttons and particularly to that type or kind which are secured to cloth or other material by means of a staple fastener which is forcibly driven through the cloth by means of an automatic button attaching machine and upset within 15 the hub of the button.

An object of the present invention is to provide a button of this type wherein the body portion is formed of non-metallic material, such as fiber, so that it will not discolor or injure the cloth, even under the 20 most adverse conditions and may be made of any desired color so as to present a neat and pleasing appearance, and to incorporate in such button novel means for upsetting and securing the prongs of a staple fastener therein.

A further object is to accomplish the aforementioned ends in a simple and practical manner, whereby the button may be 30 economically produced in large quantities, and being composed of few parts may be easily and cheaply assembled and when fastened in place will remain tightly and permanently fixed to the cloth and present 35 a neat and pleasing appearance.

With the foregoing and other objects in view, my invention consists in the improved button illustrated in the accompanying drawing and hereinafter described and 40 claimed, and in such variations and modifications thereof as will be obvious to those skilled in the art to which my invention relates, it being understood that changes may be made within the scope of what is 45 claimed without departing from the spirit thereof.

The preferred embodiment of my invention is disclosed in the accompanying drawing, wherein:

Figure 1 is a sectional view of a button embodying the characteristic features of my invention;

Figure 2 is a similar view showing the

button attached or affixed to the cloth or garment material;

55

Figure 3 is a bottom plan detail view of the non-metallic body portion of the button;

Figure 4 is a detail view in perspective of the metallic upsetting die;

Figure 5 is a sectional view of a modified form of my improved button;

Figure 6 is a bottom plan view of the non-metallic body portion and integral upsetting die; and

Figure 7 is a sectional view of a somewhat further modified form of my novel button.

Referring specifically to the several views wherein similar reference numerals designate corresponding parts throughout, my improved button comprises the non-metallic body portion A, which is preferably formed of fiber or other similar material which is hard and coherent so as to prevent breakage and is substantially chemically inert so as to resist any corroding influence, and thus capable of always presenting a neat and new appearance.

75

The non-metallic body is provided upon its lower surface with the annular groove B. A metallic hub C is provided with the upwardly and outwardly extending flange D, the diameter of the upper edge of which is originally somewhat smaller than the diameter of the entrance to the groove B, so that when pressure is applied upon the metallic hub the flange D will spread out and enter into the groove B and become permanently attached therein. The hub C is hollow and is provided with the imperforate base F, having the circular groove G 90 therein which is adapted to receive the prongs H of the staple fastener K.

95

The non-metallic body A is provided with the centrally located pocket L extending inwardly from the lower face and into which extends the base M of the upsetting die. The upsetting die includes the restricted head N which extends down within the hollow hub C and is provided with the die face O. The die face O is characterized by a central and downwardly extending projection Q, completely surrounded by the annular depression R. The annular depression R corresponds to and is located directly above, as well as in close proximity to, the 100 circular groove G of the imperforate base,

105

so that as the prongs H of the staple fastener are forcibly driven through the cloth or garment material and pierce the bottom walls of the annular groove, they will strike 5 against the face of the upsetting die and be spread, turned and swedged down upon the base of the hub and thus become permanently attached and affixed to the button, and the button in turn securely and permanently fastened to the garment material. 10 The button as thus formed will possess all the appearance and wearing qualities of the usual type of non-metallic button and, being composed of few parts, may be economically made and colored or finished to harmonize 15 with the garment to which it is to be attached.

I have found that under certain circumstances the upsetting die may be formed as 20 a part of the non-metallic body and in Figures 5 and 6 have disclosed this particular modification of my invention. The body portion A' in this type is provided with the aforementioned groove B', into which the outwardly extending flange D' is expanded and snapped or interlocked into place. The body A' is projected down within the metallic hub C' so as to form the head N' of the 25 upsetting die and the lower face of this head is provided with the annular depression O' which is adapted to spread and overturn the prongs of a staple fastener in a manner precisely similar to that described 30 in connection with the metallic die illustrated in Figure 4.

The further modified form of button illustrated in Figure 7 is formed with a non-metallic body having a groove B'' and into 40 which fits the metallic back. After the back is placed within the groove, the outer edge E'' of the groove is rolled or turned inwardly; this action taking place while the body is still in a plastic or semi-plastic state. After the edge E'' has been turned inwardly 45 and allowed to harden, it provides for the permanent securing of the metallic back in place. With the button as thus constructed it will comprehend one less part and accordingly be susceptible of cheaper manufacture. The face of the die in this instance will necessarily have to be sufficiently hard and coherent to prevent the prongs of the fastener from penetrating therein.

This type of button, similar to the type 50 as previously described, will present a neat and pleasing appearance and contain all of the characteristics of a non-metallic button.

Having thus described and explained my

invention, I claim and desire to secure by Letters Patent:

1. A button of the class described comprising a non-metallic body portion, a hollow hub interlocking with and carried by said body and provided with an imperforate base having a circular groove therein, a die carried by said body portion projecting within said hollow hub and having the upsetting face confronting and adjacent the said base and adapted to upset the prongs of a fastener against said base. 60

2. A button of the class described comprising a non-metallic body portion having a groove upon the under side thereof, a hollow metallic hub having an outwardly flaring flange fitting within said groove and interlocked with the side walls thereof, and a die carried by said body portion, having the upsetting face thereof adjacent and confronting the base of the hub and adapted to upset the prongs of a fastener directly thereagainst. 70

3. A button of the class described comprising a non-metallic body portion, a hollow hub interlocked therewith and carried thereby, said hub provided with an imperforate base having a circular groove therein, a die carried by said body portion, with the head thereof projecting down within the said hub, the face of said die head provided with a circular depression corresponding to the circular groove of the base and located symmetrically therewith, said upsetting face adapted to receive the prongs of a fastener thereagainst and to spread and upset said prongs down upon the base of the hub. 80

4. A button of the class described comprising a non-metallic body portion provided with a centrally located pocket extending inwardly from the lower face thereof, a hollow hub secured to said non-metallic body portion, a die comprising a base fitting within the inwardly extending pocket of the body portion and provided with a head projecting down within the said hollow hub, and a die face at the lower end of said head and adapted to receive the prongs of a fastener thereagainst and to spread and upset them down upon the base of the hub. 90

Signed at Waterbury, in the county of New Haven and State of Connecticut, this third day of March, A. D. 1922.

FRANKLIN R. WHITE.
